UNITED STATES PATENT OFFICE.

CHRISTOPHER J. SMITH, OF ST. LOUIS, MISSOURI.

DEVICE FOR IDENTIFYING CRIMINALS AND OTHER PERSONS THROUGH COMBINATION-PICTURE.

1,155,523.

Specification of Letters Patent.

Patented Oct. 5, 1915.

Application filed February 14, 1914. Serial No. 818,677.

To all whom it may concern:

Be it known that I, CHRISTOPHER J. SMITH, a citizen of the United States, and resident of St. Louis, Missouri, have invented certain new and useful Improvements in Devices for Identifying Criminals and other Persons through Combination-Picture, of which the following is a specification.

This invention relates to improvements in devices for identifying criminals and other persons through combination-picture, and has for its object a photograph holder adjustably mounted on a base in which the photograph of the person to be identified is held, and a plurality of transparent frames on which are mounted, painted, or otherwise applied, representations of hats, caps, suits of clothing and other articles of wearing apparel which are arranged to be placed over the picture, and to properly conform with the picture so as to properly dress the person in various costumes for identification.

Figure 1, is a perspective view of my invention. Fig. 2, is a vertical sectional view 25 of the same with a part broken away. Fig. 3, is a detail, sectional, perspective view of the photograph holder showing its construction and the manner in which it is slidably mounted on the support for adjusting the 30 same. Fig. 4, is a detail perspective view with parts broken away showing the pin hinge by which the several identification plates are detachably connected and held in connection.

35 In referring to the drawings in detail 5, indicates a case in the form of a box, in which is located supporting straps 6, on which are held the transparent plates and in which the same are housed when the device 40 is not in use. On the upper portion of the case or box, is provided a top 7, consisting of a frame having the center portion open as indicated by the numeral 8, and on the top thereof is provided a cleat 9, which acts as 45 a support for a plate 10 and to which said plate is firmly secured; this plate 10 is constructed of thin metal, and is slit at the points indicated by the numeral 11; the center portion 12 between the slits is bent upwardly 50 providing sufficient space for the insertion of the strip 13, forming a part of the photograph holder 14, said strip 13 being bent downwardly after the photograph holder has been slit at the points indicated by the 55 numeral 15. The two sides and bottom edge

of the photograph holder are looped as indicated by the numeral 16, which acts as a support for the edge of the photograph and holds the same firmly in position.

On the bottom of the strip 13, and centrally located is secured a handle 17, which extends downwardly, and then outwardly terminating in a hand portion, this handle projecting through a slot 18, formed in the side of the casing or box, and by means of 60 this handle the entire photograph plate can be shifted to any desired position on the top so as to properly correspond with the articles of wearing apparel which are designed on the transparent frames 19, when folded 65 over or laid on the top of the photograph.

The transparent frames 19, are provided with hinges 20, of the pin type, and on the box is also provided a corresponding hinge member in which the pin 21 of the hinge is 70 permitted to be inserted when placing the transparent plates in position for use.

In the box and on the slide 6, are located numerous plates having various designs of 75 wearing apparel imprinted thereon, and can be easily and readily removed from the box and placed in position so as to properly 80 dress the person for the purpose of identification.

The essential feature of my invention is to 85 construct a device on which a photograph is placed, and a transparent plate placed over the same on which is imprinted or otherwise applied, various representations of 90 wearing apparel, either in black or in colors, and which are so arranged as to dress the photograph for the purpose of identifying a person. It has oftentimes occurred that in identifying criminals, the person wishing 95 to make the identification may not recognize the criminal by viewing the photograph taken by the Bertillion system, but by placing a hat, cap, or body garment over the photograph the facial expressions is changed and by that manner the person may be identified for the reason that the person may have recognized the criminal by having a certain color or suit or certain style of headgear.

When the device is not in use the identification plates are removed and placed inside of the box out of the way.

Having fully described my invention what I claim is:

1. A device of the class described compris- 110

ing a case, a photograph supporting plate adjustably mounted on the top of said case and a plurality of transparent plates on which is imprinted various articles of wearing apparel hingedly mounted on four sides of said case and arranged to be folded over the photographic supporting plate, substantially as specified.

2. A device of the class described comprising a rectangular case, a photograph supporting plate mounted on the top of the case and arranged to be shifted to various positions on said top; a plurality of transparent plates hinged to the sides of the case and arranged to be folded over the photograph,

each of said transparent plates provided with a picture of a certain article of wearing apparel which is to be placed over the photograph for dressing the picture; and slides located in the frame for supporting various plates containing different articles of wearing apparel, substantially as specified. 20

In testimony whereof I have signed my name to this specification, in presence of two subscribing witnesses.

CHRISTOPHER J. SMITH.
